UNITED STATES PATENT OFFICE

HARRY J. LEBHERZ, OF FREDERICK, MARYLAND, ASSIGNOR TO THE EVEREDY COMPANY, OF FREDERICK, MARYLAND, A CORPORATION OF MARYLAND

BOTTLE CAPPER

Application filed October 12, 1929. Serial No. 399,259.

My invention relates broadly to bottle cappers and more particularly to a manually operated bottle capping tool.

One of the objects of my invention is to provide a construction of hand operated bottle capper which will enable relatively large force to be applied in affixing a crown cap upon a bottle by movement of a plunger downwardly upon the crown cap of a bottle.

10 Another object of my invention is to provide a construction of plunger type bottle capper having means for readily adjusting the position of the plunger for capping bottles of different heights.

15 A further object of my invention is to provide a plunger type bottle capping tool having the operating parts thereof substantially enclosed by the standard which supports the bottle capping mechanism with

20 means for readily adjusting the position of the bottle capping plunger with respect to the standard which supports the plunger, thus enabling the bottle capping tool to be readily used on bottles of different sizes.

25 A still further object of my invention is to provide a plunger type bottle capping tool in which pressure may be applied for actuating a plunger with respect to a bottle by the movement of a hand lever in one direc-

30 tion which pressure is removed from the plunger and the plunger adjusted in position with respect to the supporting standard for utilizing the bottle capping tool upon bottles of different sizes.

35 Other and further objects of my invention reside in the construction of bottle capping tool set forth in the following specification and illustrated in the accompanying drawings, in which:

40 Figure 1 is a side elevation of a bottle capping machine constructed in accordance with my invention; Fig. 2 is a front elevation thereof; Fig. 3 is a fragmentary side elevation with the operating handle turned for-
wardly in the direction of the arrow in order to apply a cap to a bottle; Fig. 4 is a similar view but with the handle thrown rear-
wardly in the direction of the arrow and showing the stop arm abutting the frame, in
order to raise or lower the rack gear plunger;

Fig. 5 is a detailed vertical sectional view on a somewhat larger scale taken on line 5-5 of Fig. 6; Fig. 6 is a horizontal sectional view taken on line 6-6 of Fig. 2; and Fig. 7 is a perspective view of the mutilated gear and adjacent parts. 55

Referring to the drawings in more detail, reference character 1 designates the standard for the bottle capping tool of my invention. The standard may be cast integral 60 with the base 2 and the head 3 providing an extremely simple construction which is rigid and capable of inexpensive manufacture on a quantity production basis. The head 3 is

provided with a vertically extending bore 8 65 therein and immediately behind the bore 8 there is provided an enlarged horizontally extending bore 4 which communicates with the bore 8. A shaft 5 extends through bore 4 on a horizontal axis. The shaft 5 being 70 milled to provide gear teeth 6 throughout a portion of its circumference and being ground into a flattened portion 7 at one side thereof. A plunger 9 passes through bore 8 and is provided with a rack 10 at one side 75 thereof, which is engageable by the teeth 6 of rotary shaft 5. Plunger 9 carries a bottle capping throat 18 in the lower extremity thereof, which throat is placed over the neck 80 of a bottle supported on base 2 during the process of applying a crown cap to the bottle. The capping mechanism is assembled by means of spring latch 11 having spring arms 11a which fit into the groove 5b formed on the portion 5a of the rotary shaft 5 adjacent 85 the end 5c thereof, the spring arms 11a ex-
tending around the groove 5b in such manner that the rotary shaft 5 is secured in position

90 for rotative movement but prevented from moving transversely and thus becoming dislodged from the bottle capping head. The shaft 5 is rotated by means of a lever 12 hav-
ing a handle 14 thereon which extends through shaft 5 as shown more clearly in Fig. 7. A collar 15 having a sleeve 15c fits 95 over the shaft 5. The sleeve 15c has dia-
metrically opposite notches 15d cut therein, which notches must be registered with lever 12 in securing collar 15 in proper position 100 with respect to rotatable shaft member 5.

that is in a position where abutting arm 15a and hook 15b are properly positioned for the proper cooperation of the parts of the bottle capping throat. Collar 15 carries the limiting stop 15a which extends radially from collar 15 and hook-shaped member 15b angularly displaced at approximately 90 degrees around the collar 15. A coil spring 16 extends between the hook-shaped member 15b and the fixed point 17 on the standard 1 for exerting a turning torque on collar 15 and through sleeve 15c and the interlocking of notches 15b with lever 12 upon shaft 5, thus restoring lever 12 to a bottle capping position and elevating plunger 9 after each successive bottle capping operation. Where it is desired to adjust the position of plunger 9 with respect to the bottle on which the bottle capping tool is operated, the hand lever 12 may be reversed in its position until the end of the limiting stop 15a strikes the outstanding rib 1a of standard 1, thereby bringing the flattener portion 7 adjacent the teeth 10 on plunger 9, enabling the plunger to be readily slipped upwardly or moved downwardly to a selected bottle capping position.

Fig. 4 illustrates the position of hand lever 12 when plunger 9 is being adjusted vertically to a position for applying crown caps to bottles of selected sizes. Fig. 3 shows a hand lever moved to an opposite position where the teeth 6 on shaft 5 again mesh with the teeth 10 on plunger 9 and enable the plunger to be moved downwardly under pressure for applying a crown cap to a bottle. The bottle capping throat 18 is provided with a double seal die head 19 by which a crown cap may be permanently sealed upon the neck of the bottle.

The double seal feature which I employ in the capping throat or die head is shown more fully in my Letters Patent No. 1,421,698, issued July 4, 1922.

The plunger type bottle capper described herein has been found to be extremely practical in its manufacture and production, and while I have described a preferred embodiment of my invention, I desire that it be understood that modifications may be made and that no limitations upon my invention are intended other than are imposed by the scope of the appended claims.

What I claim as new and desire to secure by Letters Patent of the United States is as follows:

1. A bottle capping tool comprising a standard having a base and a head integrally connected therewith, a plunger passing through said head, gear teeth cut in one side of said plunger, a capping throat carried by the lower extremity of said plunger, a rotary shaft member extending through said head normal to said plunger, a lever for revolving said shaft, said shaft having gear teeth cut throughout one portion of the periphery

thereof and being flattened throughout the remaining portion of the periphery thereof, a collar insertable over said shaft, spring means connected between one point on said collar and said standard, and a radially extending stop projecting from another portion of said collar, whereby said lever operates to rotate said shaft against the tension of said spring for effecting a bottle capping operation to a limiting position determined by said stop for moving the teeth on said shaft out of engagement with the teeth on said rack for allowing adjustment in the position of said plunger above said base.

2. A bottle capping tool comprising a standard having a base and a head connected thereto, a plunger movable through the head of said standard, a bottle capping throat carried by the lower extremity of said plunger, gear teeth cut in one side of said plunger, a geared shaft extending through said head normal to the axis of said plunger, a lever for actuating said shaft, a sleeve member carried by said shaft, a projection on one side of said sleeve member, a hook-shaped member connected to said sleeve at a point angularly spaced from said projection, spring means extending between a point on said standard and said hook-shaped member for exerting a turning torque on said shaft for returning said plunger to a bottle capping position after each successive bottle capping operation, said projection abutting with a portion of said standard when said lever is moved to a position for disengaging said geared shaft from the teeth on said plunger for allowing said bottle capping throat to be adjusted to a selected position above said base.

3. In a bottle capping tool a standard having a base and a head, a plunger passing through said head, a bottle capping throat carried by said plunger, teeth formed in one side of said plunger, a shaft extending through said head normal to the axis of said plunger, one side of said shaft being flattened and the remaining periphery of said shaft having gear teeth cut therein, means for latching said shaft in position in said head, a sleeve insertable over said shaft, said sleeve having diametrically opposed notches cut therein, a hand operated lever extending through said shaft and through the notches cut in said sleeve for rotating said sleeve simultaneously with the rotary movement of said lever, tension means connected to said sleeve, a stop projecting from said sleeve, whereby said shaft may be rotated to a position presenting the flattened side thereof to the teeth formed on said plunger for allowing adjustment of the position of said plunger above said base and engaging the teeth on said shaft with the teeth on said plunger for actuating said plunger during a bottle capping operation.

4. An actuating device for a bottle capping tool having a plunger with gear teeth cut in one side thereof, an angularly movable shaft extending normal to the axis of the plunger, said shaft being flattened on one side thereof and having teeth cut throughout the remaining periphery thereof and engageable with the teeth on said plunger, and a hand actuated lever extending through said shaft, 10 a sleeve member positioned on said shaft and notched for engagement by said lever, an arm projecting from said sleeve member for abutment with said bottle capping tool for limiting the rotation of said shaft, 15 resilient means connected between a point on said bottle capping tool and a point on said sleeve for urging said shaft to a position where the teeth on said shaft engage the teeth on said plunger, said hand lever being angularly shiftable to a position determined 20 by the abutment of said projection with said bottle capping tool for disengaging the teeth on said shaft from the teeth on said plunger for allowing vertical adjustment of said 25 plunger.

5. A bottle capping tool comprising a base, an integrally connected standard, said standard being curved from a position adjacent one end of said base to a position substantially over said base, and means carried by said standard for pressing a crown cap upon a bottle supported on said base, said means including an angularly movable lever and a device connected therewith abutting with the 30 curved top of said standard for limiting the movement of said lever in one of its extreme positions.

6. In a bottle capping tool, a base, a standard integrally connected with said base and 40 curved over and extending in a line which changes its direction from a vertical position to a position directly over said base, bottle capping mechanism carried by the extremity of said standard directly over said base and 45 arranged for successively applying crown caps upon bottles supportable upon said base, said mechanism including an angularly movable hand lever and a projecting member connected therewith and abutting with the 50 curved portion of said standard for forming a positive stop for said lever in one of its extreme positions.

7. In a bottle capping tool, a base, a standard integrally connected with said base and 55 extending vertically therefrom and curved adjacent the top thereof to a position substantially over said base and bottle capping mechanism carried by the upper portion of 60 said standard for successively applying crown caps to bottles supportable on said base, said mechanism including an angularly movable lever and a member projecting in a plane parallel thereto at an acute angle with 65 respect to said lever and abutting with the

curved portion of said standard in one of the extreme positions of said lever.

8. A bottle capping tool, a base, a standard integrally connected with said base and projecting upwardly therefrom, said standard having a curved portion adjacent the top thereof terminating substantially over said base and bottle capping mechanism carried by the curved portion of said standard for successively applying crown caps to bottles supportable on said base, said mechanism including an angularly movable lever and a projecting member connected therewith at an acute angle and abutting with the curved portion of said standard in one of the extreme 70 positions of said lever.

9. In a bottle capping tool, a base, a standard connected to one side of said base, said standard including a vertical portion and an upper curved portion, said vertical portion extending in a direction substantially tangent to the upper curved portion, and bottle capping mechanism carried by said upper curved portion for successively applying caps to bottles supportable on said base, said mechanism including an angularly movable lever and a projection connected therewith and abutting with the curved portion of said standard in one of the extreme 75 positions of said lever.

In testimony whereof I affix my signature. 80
